[57]**CLAIM**

The ornamental design for a lint remover, as shown and described.

DESCRIPTION

FIG. 1 is an exploded perspective view of a line remover, showing my new design;

FIG. 2 is a perspective view showing the lint remover as it appears when partially assembled;

FIG. 3 is a side elevational view of the partially assembled lint remover;

FIG. 4 is a left end elevational view thereof;

FIG. 5 is a right end elevational view thereof;

FIG. 6 is a side elevational view of the fully assembled lint remover;

FIG. 7 is an exploded perspective view of a second embodiment of a lint remover;

FIG. 8 is a top plan view thereof with the tape roll removed for clarity;

FIG. 9 is a left end elevational view thereof;

FIG. 10 is a left end elevational view of a third embodiment of a lint remover;

FIG. 11 is a left end elevational view of a fourth embodiment of a lint remover;

FIG. 12 is a partial cross sectional view of the embodiment shown in FIG. 11.
